United States Patent Office

Des. 227,538
Patented July 3, 1973

227,538

CASSEROLE

Fred Press, White Plains, N.Y., assignor to House
Mates Inc., Hartsdale, N.Y.

Filed June 23, 1971, Ser. No. 156,174

Term of patent 14 years

Int. Cl. D7—02

U.S. Cl. D7—85

FIG. 1 is a perspective view of a casserole showing my new design;

FIG. 2 is a top plan view with a quarter of the cover member broken away for convenience of illustration; and

FIG. 3 is an elevational view, partly in section on the line 3—3 of FIG. 2.

I claim:

The ornamental design for a casserole, substantially as shown and described.
